UNITED STATES PATENT OFFICE.

BENJAMIN F. DENGLER, OF LOS ANGELES, CALIFORNIA.

BASE-BALL-GAME BOARD.

1,092,979.

Specification of Letters Patent. Patented Apr. 14, 1914.

Application filed April 21, 1913. Serial No. 762,726.

To all whom it may concern:

Be it known that I, BENJAMIN F. DENGLER, a citizen of the United States, residing at Los Angeles, in the county of Los Angeles 5 and State of California, have invented a new and useful Base-Ball-Game Board, of which the following is a specification.

This invention relates to a game board apparatus provided with means whereby the 10 operations of pitching and batting the ball may be carried out on a small scale suitable for indoor play and in which the plays may be counted as base runs and may be determined according to the manner in which the 15 ball is batted, so as to simulate as far as possible, the plays which actually take place when the ball is batted to a certain part of the field.

Another object of the invention is to provide 20 a base ball game board in which the count or value of the plays is determined by skill on the part of the batter rather than by mere chance.

Other objects of the invention will appear 25 hereinafter.

The accompanying drawings illustrate an embodiment of the invention, and referring thereto:

Figure 1 is a plan view of the board. 30 Fig. 2 is a partial section, on line x^2-x^2 , Fig. 1, of the portion of the board near the home plate. Fig. 3 is a section on line x^3-x^3 , in Fig. 1.

The apparatus comprises a flat board or 35 platform 1, having a fence or boundary wall 2 extending around the same and projecting above the board to form an obstruction for the ball to keep it from going out of bounds. This board or platform is provided 40 with a rectangular portion or field 2' representing the base ball field and with a forward extension 3 from said field terminating in a depressed portion 4. The rear walls 1' for the field portion of the board are 45 placed obliquely to the longitudinal axis of the board and the front boundaries of the field are parallel to the rear boundaries, forming a square, set obliquely to the axis of the board. Said front boundaries are 50 marked by boundary strips 6 which extend

from the side walls of the board forwardly and inwardly. Obstructing strips 8 extend across the field transversely to the longitudinal axis of the board and other obstructing strips 9 extend across the strips 8 and parallel to the oblique sides of the field, said crossing strips 8 and 9 forming a net work, so that the field is divided by said strips into a large number of pockets or depressions 55 11 adapted to receive the ball when it is batted and to bring the ball to rest in definite positions. Marks 10 are provided on said strips or on the field portion of the board to indicate certain zones or areas within which the ball may land or come to rest, the runs or 60 plays being counted or determined with reference to such zones or areas. An area 12 at the front of the field is left clear or free from the obstructing strips 8 and 9, the pitcher's box 13 and home plate 14 being located 65 within this area, the home plate being at the front corner of the field portion of the board and being preferably on an inclined upper face of a block 16 on the board. Bases marked 1, 2 and 3 are also provided 70 in the field, the said bases, pitcher's box 13 and home plate being indicated by suitably marking the surfaces at these points. Adjacent to the first and third bases, pockets 15 are formed by strips 15' on the board, delineating areas within which the field ball 75 is assumed to be within reach of the baseman. At the front end of the field, means are provided for movably supporting a bat. For this purpose channels 17 are formed in 80 the board 1 extending rearwardly from the depression 4 and metallic plates 18 are secured on said board, adjacent said channels and extending over the channels, and slotted as at 19 to form guideways and bearing supports for a pedestal or post 21, which is provided 85 near its lower end with an annular groove 22 adapted to engage the said plates to permit the post to slide along the guideway to any desired position and to turn therein. The bat indicated at 23, is secured to 90 said post and provided with a handle 24, the said bat being adapted to extend in front of and somewhat above the upper front edge of the inclined member 16 bearing 95 100

the home plate. Said guideways are provided at each side of the home plate for use with the right or left hand respectively.

In the depression 4 at the forward end of 5 the board, means may be provided for facilitating tallying or keeping score of the game, said board being provided, for example, with two series of holes 25 adapted to receive counter pins 26. Two series of holes 28 10 may also be provided in the board for receiving pins to score or count the number of "outs" for either side.

Any suitable number of counters 30 in the 15 form of checks or having any fanciful form, for example, images of ball players, may be used in connection with this board to represent the players for each side. It will be understood, however, that the game is not limited to any given number of players so 20 long as there is an equal number on each side.

The board is provided with marks or instructions 33 indicating the significance or effect of a ball landing in any one of the 25 zones or areas delimited by the crossing strips 8 and 9 aforesaid, these instructions being, for example, impressed on the strips 9 so that each zone or area contains the instructions corresponding thereto and indicating the effect on the batter or a runner 30 of the side which is "in" due to landing of a ball in that zone, the instructions being preferably such that the effect on the batter and man on base conforms to the general 35 or average effect of the ball being batted to that portion of the field, having regard to the average chance of the ball being caught by a baseman or fielder. In addition to such instruction, a set of rules may 40 be furnished with the game board, for example: "This game is played by two or more persons, one side opposing the other, each side composed of any even number of persons. Nine innings constitute a game, 45 and the side scoring the most runs wins. Three outs retire a side. If the batter fails to hit any of the three fair balls delivered over the home plate, he is out and the next player in turn bats, if the batter just retiring 50 is not the third out. Four pitched balls that fail to pass over the home plate which the batter has not struck at gives the batter one base. If the bases are all full, it entitles each man on bases to advance one base, 55 or if a man is on first base and none on second then the man on first base advances to second base. All others remain as they are. Any batter knocking the ball over the enclosed field is out. When rolling the ball 60 for the batter to strike at, the ball must be started to roll any place in open space where the pitcher's box is located. If not started in this space no ball or strike can be

called. A foul ball unless accounted for on board, is not considered. The batter must 65 take handle of bat in fingers and strike at pitched ball he considers good. The batter must not let loose of bat when striking. If he purposely twirls the bat at a delivered ball he is out. The board is marked for all 70 other plays."

The game is played as follows: One of the side which is "in" grasps the bat by the handle 14 thereof and one of the other side, acting as pitcher, rolls the ball, indicated at 75 32, from the vicinity of the pitcher's box, in such manner that it will pass up on the incline 16 and the batter will at this moment attempt to hit the ball to drive it out into the field, the direction of delivery of 80 the ball depending largely on the angle and speed with which the bat strikes the ball and also on the position of the bat on its support. In this connection it may be stated that the height of the front end of the incline is sufficient to allow the ball to drop under the bat in case the bat is not held close enough to the upper end of the incline. The control of the place of landing the batted ball is, therefore, a matter of considerable 85 skill and not of mere chance. The ball after leaving the bat, in case it is a fair ball, lands on some portion of the field and is obstructed in running over the field by the strips 8 and 9, so as to be brought to 90 rest in one of the pockets 11, whereupon the counter 30 corresponding to the batter is either counted out or is moved to the base indicated by the instructions in the zone. As the game proceeds any man on base, 95 100 when a fair ball is batted, is subject to advance or to being put out, according to the instructions in the zone in which the ball lands.

What I claim is:

1. A base ball game board provided with 105 marks indicating home plate and bases and pitcher's box, with a field portion including said marks, and a bat movably mounted adjacent the home plate, said board being provided with a guideway and said bat being provided with a post slidably and rotatably mounted in said guideway.

2. A base ball game board provided with marks indicating home plate and bases and pitcher's box, with a field portion including 110 said marks, and a bat movably mounted adjacent the home plate, said field portion of the board being provided with obstructing strips crossing one another to form a net 115 work with depressions between said strips for retarding the movement of the balls over the field.

3. A base ball game board provided with marks indicating home plate and bases and 120 pitcher's box, with a field portion including 125

said marks, and a bat movably mounted adjacent the home plate, said field portion of the board being provided with obstructing strips extending across the field forming, between said strips, depressions for receiving the ball and obstructing its motion over the board, and marks dividing said field portion into zones.

In testimony whereof, I have hereunto set my hand at Los Angeles, California, this 10 12th day of April, 1913.

BENJAMIN F. DENGLER.

In presence of—

ARTHUR P. KNIGHT,
MARTHA M. LANGE.
